UNITED STATES PATENT OFFICE.

HENRY F. SHAFFNER, OF WINSTON-SALEM, NORTH CAROLINA, ASSIGNOR TO BRIGGS-SHAFFNER COMPANY, OF WINSTON-SALEM, NORTH CAROLINA.

CARTON-MAKING MACHINE.

Application filed February 27, 1924. Serial No. 695,431.

To all whom it may concern:

Be it known that I, HENRY F. SHAFFNER, a citizen of the United States, and resident of Winston-Salem, in the county of Forsyth and State of North Carolina, have invented certain new and useful Improvements in Carton-Making Machines, of which the following is a specification.

My invention relates generally to an attachment for a machine of the type shown in the patent to Ludington, 561,332, for making paper cups or cartons for cigarettes, snuff, or the like, and is illustrated in connection with a machine of this character although not limited thereto.

In the machine shown in the patent to Ludington, a magazine is provided with a plurality of blanks and a series of formers or mandrels are rotated step by step through four different positions in each of which they remain stationary for an interval. In the first position a blank is taken from the magazine, gummed appropriately and placed on the former where it is held by a clip. The paper is also folded and the side glued. The former then moves one-quarter of a revolution to the second position where the first folds of the end are made. Another step brings the former to the third position where the end is completed and the carton is then fully formed. The final step to the fourth position brings the former to a point where the finished cup or carton is stripped off the former. The operation is then repeated. Of course when the machine is running, all four formers are in use and all stages are attained in sequence by each former.

It has been found that this method of manufacture produced a cup or carton the bottom of which lacked sufficient stiffness for proper durability in the filling and use of the same.

My invention relates to an attachment by which a piece of cardboard will be placed in the bottom of each cup formed as indicated above and glued therein, thus imparting sufficient firmness and strength to the completed cup.

An object of the invention is to provide an attachment of this character which will be applicable to the machine with very few changes and which will not interfere in any way with the operation of the other instrumentalities.

Another object is to provide means for taking a card from the bottom of the magazine and placing it on the end of the former, where it is held throughout the manufacture of the cup or carton.

Other objects will be apparent from the following detailed description and the appended claims.

In the drawings:

Figure 1 is a perspective view of the machine having my attachment applied thereto.

Figure 2 is a side elevation of the attachment and operating means therefor with the parts in the position which they occupy just before the card is placed upon the end of the former.

Figure 3 is a portion of the card feeding mechanism with the parts in normal position.

Figure 4 is a view of the same parts in fully operated position.

Figure 5 is a side elevation of a portion of the mechanism shown in Figure 2, viewed from the opposite side.

Figure 6 is a vertical section, with parts in elevation, of the former, card magazine, and card feeding device in fully operated position.

Figure 7 is a section on the line 7—7 of Figure 6.

Figure 8 is a section on the line 8—8 of Figure 6.

Figure 9 is a detail showing a portion of the card carrying slide.

Figure 10 is a perspective view of the bracket which supports the card magazine and the feeding slide.

Figure 11 is a section through the member shown in Figure 12.

Figure 12 is a fragmental plan showing the opening through which the completed cups drop.

Figure 13 is a perspective view of the bracket supporting the operating parts.

Figure 14 is a perspective view of the upper portion of the card magazine.

Figure 15 shows face and edge views of the card used.

Figure 1 shows a view of the entire machine which has a frame A and a bracket or shelf B for the support of the operative parts. Power is transmitted to the shaft C from any suitable source and drives the machine. A member D is given a step-by-

- step rotary movement, and carries four formers or mandrels E. This member D stops momentarily at four points in its revolution so as to bring each former successively into four different positions, two of which are designated in Figure 1 at II and III. When in the first position which is diametrically opposite to position III, a sheet of paper is taken from the magazine 10 F by mechanism G and placed upon the former where it is held by clamp members e. The paper is appropriately gummed at one side and end, and is folded in tubular form about the former.
- 15 When the former stops in the second position, certain mechanism G partially folds the bottom, and in the third position this folding is completed so that the cup or carton has its completed form. In the 20 final position, diametrically opposite to position II, the finished cup is stripped from the former, thus completing the sequence of operations. The operation thus far described is or may be substantially the same 25 as that of the Ludington patent, and the structure of the machine is similar to that there disclosed.
- My invention relates to an attachment for placing a pasteboard bottom in the cup or 30 carton formed by the machine briefly described above. It involves only slight modification of the frame of the machine and practically no modification of the mode of operation.
- 35 A shaft 1 driven in any suitable manner carries a sprocket wheel 2 about which passes a sprocket chain 3 which passes about a sprocket wheel 4 on a shaft 5 supported in bearings in a bracket 6 on the frame of the machine. An arm 7 on said shaft has a cam 8 pinned thereto by a pin 9 and the cam carries a roller 10 which works in a groove 11 in a cross head 12.
- 40 A bracket member 13 (see Figure 13) has a flat portion overlying the shelf B to which it is fastened by bolts or screws passing through holes 15. It also has a downwardly extending ledge portion 16 provided with bores 17 and 18, as well as an arm 19 which has an offset 20 at its lower end provided with bores 21, 22 and 23. A stop screw 24 is threaded through the member 13 and held in adjusted position by a lock nut 25.
- 45 Associated with the cross head 12 and the bracket 13 are three rods 26, 27 and 28. The rod 26 passes through the bores 17 and 21 and through a bore in the cross head. It is revoluble in said bores but is prevented from endwise movement relative to the cross 50 head by means of collars 29 and 30 fitting above and below the cross head and fastened to the rod. The rod 26 is normally held in one position by a spring 31 fastened at one end to a pin 32 on the collar 29 and at its other end to a pin 33 on the cross head.
- 55 Fastened to the rod 26 intermediate its ends is a collar 34 terminating in a cam finger 35 the purpose of which will be hereinafter explained. Carried by the upper end of the rod 26 is an arm 36 having an offset lip 37 at its free end.
- 60 The rod 27 slides through bore 20 and a bore in the cross head. It carries collars 38 and 39 held thereon by set screws above and below the cross head so as to allow the rod a definite movement independent of the cross head. At its upper end it is provided with a block 40 having an edge cut out at 41 to provide an engaging surface for the finger 35 which surface forms a cam. 65 Normally the block 40 rests above the member 20 and its upper limit of movement is determined by the set screw 24. In this position, shown for example in dotted lines in Figure 5, the finger 35 rests in the cut out 41 and the collar 38 is in engagement with the cross head. As hereinafter pointed out, Figure 5 represents an intermediate position of the parts. The rods 26 and 27 act to operate mechanism for stripping the 70 finished carton or cup from the former, and in themselves are not new.
- 75 The rod 28 slides through openings 18 and 23 and a bore in the cross head, but does not receive its movement from the cross head which merely acts as a guide for said rod. Pivotaly mounted in a bracket 42 carried by the frame is an angular arm 43 having pivoted at 44 to its end an upward 80 extending arm 45 whose upper end is pivoted on a pin 46 in a cut out 47 of a collar 48 that is fast on the rod 28. Carried by the arm 43 is a roller 49 with which contacts the edge of the cam 8. A collar 50 is carried by the upper portion of the rod 28 and limits its movement. A link 51 pivoted to the arm 43 has a spring 52 connected thereto and the other end of the 85 spring is fast to a hook 53 carried by the frame.
- 90 The rods 26 and 27 coact to strip the completed cup or carton from the former while the rod 28 operates mechanism to feed into position the piece of cardboard which is to form the bottom of the next cup to be made. 95 The means by which these operations are performed will now be described.
- 98 Each former has a central cylindrical bore in which slides a plunger 54 which is open at its upper end and a spring 55 contained within the plunger is fastened at one end thereto and at its other end to a pin 56. Through one side of the former a slot 57 communicates with the cylindrical bore and the plunger has an angular finger 105 58 attached thereto and extending through the bore. When the parts are in normal position, shown for example in dotted lines in Figure 2, the lip 37 is in position to engage the finger 58 on the downward move- 110
- 115
- 120
- 125
- 130

ment of the former. As the cross head 12 and rods 26 and 27 move downward from position X (Figure 2) to position Y the plunger 54 is pulled down also and strips the completed cup off the former. At position Y, the block 40 engages member 20 and cannot move any farther. The rod 26 continues to move and the finger 35 is cammed to one side by the cam groove 41, turning the rod 26 so that the lip 37 slips off of the finger 58 permitting the spring 55 to return the plunger to normal position within the former.

The rod 28 has a pin 59 at its upper end, and this pin engages and operates mechanism for feeding a card from the magazine to its position on the former. This will now be described.

Fitting in a cut out 60 of the shelf B is a member 61 that is fastened to said shelf by bolts passing through holes 62 in the member and cooperating holes 63 in the shelf. A space 64 is left through which the cups pass as stripped from the former. The member 61 has an upstanding arm 65 to which the card magazine 66 is fastened and a pair of perforated ears 67 which provide a bearing for a certain operating shaft. It also has a groove 68 within which is placed the card feeding slide mechanism.

The card magazine consists of a member fixed to the arm 65 and having one open side, together with a removable container 69 of similar shape fitting therein and containing the cards. A weight 70 is placed upon the cards, and the container has an ear 71 through which passes a screw 72 which may engage or be threaded into the magazine proper 66. The cards Z are of any desired size and thickness and are shown in Figure 15.

An upwardly extending bracket 73 supports one end of a shaft 74, the other end of which has bearing in an enlarged portion 75 of the side of the magazine 66. A shaft 76 mounted in the ears 67 has an arm 77 provided at its end with an open slot 78 in which engages the pin 59 carried by the rod 28. Another arm 79 is carried by the shaft 76 and has a slot 80 therein in which works a pin at one end of an adjustable link 81 the other end of which is pivoted at 82 to an arm 83 carried by the shaft 74. The free end of the arm 83 is provided with a slot 84 which cooperates with a pin 85 in the card slide.

Two side pieces 86 fit within the channel 68 in the member 61 and attached to their ends are members 87 which are also fastened to rectangular rods 88 that are spaced from the members 86 to form guide slots 89. The card slide 90 has side extensions 91 which fit within the slots 89 so that the slide is guided in a right line. In a depression in the inner end of the card slide is mounted a mov-

able member 92 having its edges slightly beveled and carrying two lugs 93 on its upper face. These lugs have a straight face at one end and are beveled off at the other end. A rod 94 fastened at one end to the member 92 extends through a bore in the slide and is attached at its lower end to operating means hereinafter described. Two other rods 96 also fastened to the member 92 extend downward through bores in the slide 75 and have nuts on their free threaded ends. Springs 97 surround these rods between the nuts and the slide, and the tension of the springs can be adjusted by moving the nuts. These springs tend to hold the member 92 in 80 its depression in the slide 90 as shown in Figure 9. A downward projection 98 at the inner end of the slide acts as a stop for the return movement thereof. When the parts are in normal position as shown in Figures 85 1 and 3, the member 92 of the slide underlies the card magazine with the projections 93 at one side of the card. A movement of the slide brought about by a downward movement of the rod 28 acting through parts 59 90 and 76 to 85 inclusive, causes the projections 93 to catch the lowermost card in the magazine and move it through the cut out side of the magazine toward the former. When it is in a position close to the former, the cup stripping plunger 54 is released by the lip 37 and returns to normal position 95 out of the path of the card moving slide which is then moved underneath the former by the further downward movement of the 100 rod 28.

Referring particularly to Figure 6, it will be noted that the member 92 carrying the card is lifted in the following manner. The card slide has pivoted thereto at 99 a lever 100 having a lower cam surface at 101 and carries a finger 102 which underlies the rod 94 and will raise the rod and member 92 when it is moved upwardly. An arm 103 is pivoted to the slide to swing freely, and this arm carries a roller 104 intermediate its ends and another roller 105 at its end. The roller 104 supports the lever 100 and cooperates with the cam surface 101. The roller 105 cooperates with a cam member 106 115 having an angular portion 107 fastened by a screw bolt 108 to the member 61. As the card slide moves inward the roller 105 will ride up the cam member 106 and raise the lever 100 upwardly, thereby lifting the rod 120 94 and member 92 which carries the card Z into the position shown in Figs. 4 and 6.

Each former has two spring members 109 set in opposite sides, the lower ends of which are inturned at 110 as shown in Figure 8. 125 The upward movement of the member 92 with the card Z will snap the card into position against the end of the former where it will be grasped and held by the inturned spring ends. As soon as the roller 105 130

removes off the cam member 106 which takes place just an instant after the parts reach the Figure 6 position the arm 103 will swing past the vertical position and be stopped by contact with a spring 111 attached to the slide. This will permit the member 92 to drop sufficiently so that the former may begin to move while the card slide is just beginning its return movement. In the return movement the arm 103 will swing in the opposite direction as the roller 105 passes back over the cam 106 but this will not raise the lever 100 owing to the arrangement of the cam surface 101. Another card has by this time been forced to the bottom of the card magazine, but the return movement of the slide will not be hindered thereby since the beveled ends of the projections 93 will cam the card upwardly enough to permit the passage of the slide.

It is believed that the operation of the machine will be clear from the above description. The card feeding attachment has been added to the machine without interfering with the normal operation of any of the parts of the main machine and will feed and position a card on each former just after the completed cup has been stripped therefrom. It is obvious that many detail changes may be made without departing from the spirit of the invention, and it is understood that the invention is limited only by the scope of the appended claims.

I claim as my invention:

26. 1. In a machine for making paper cups or cartons upon a former, spring clips at the end of the former, a card magazine, and means for transferring a card from said magazine to the end of the former where it is held by said spring clips.

2. In a machine for making paper cups or cartons upon a former, a card magazine, means for moving the card successively in two directions to a position against the end of the former, and clips on said former which have edges engaging the card and holding it when positioned thereon.

3. In a machine for making paper cups or cartons upon a former, a card magazine, means for moving the card to a position beneath the end of the former, means for moving the card at right angles to its first movement to engage the former, and means on said former for engaging and holding said card.

4. In a machine for making paper cups or cartons upon a former, a card magazine, a card slide adapted to reciprocate beneath said magazine, a card holder carried by said slide and movable at right angles thereto, and means for giving the slide and holder their movements to position a card against the end of the former.

5. In a machine for making paper cups or cartons upon a former, a card magazine,

a card slide adapted to reciprocate beneath said magazine, a card holder carried by the slide and movable at right angles thereto, means for giving the slide and holder their movements to position a card against the end of the former, and spring clips carried by the former for receiving and holding the card.

6. In a machine for making paper cups or cartons upon a former, a card magazine, 75 a card slide adapted to transfer a card from the magazine to a position beneath said former, a card holder carried by the slide and movable relative thereto, and means whereby the latter portion of the movement 80 of the slide will cause a movement of the card holder.

7. In a machine for making paper cups or cartons upon a former, a card magazine, a card slide, means for moving the card 85 slide endwise, a card holder carried by the slide and adapted to transfer a card from the magazine to the former, means whereby the movement of the slide will cause a movement of the card holder relative thereto, and spring means for returning the holder to normal position relative to the slide after the card has been positioned upon the former.

8. In a machine for making paper cups or cartons upon a former, a card magazine, a slide mounted to reciprocate beneath said magazine, a card holder adapted to move a card from the magazine when travelling in one direction, means for moving said card holder at an angle to the travel of the slide, and means on the former for receiving the card from the holder and retaining the same.

9. In a machine for making paper cups or cartons upon a former, a card magazine, a slide mounted to reciprocate beneath the magazine, a card holder movably mounted on the slide, means for retaining the card holder in normal position, means on said card holder adapted to withdraw a card from the magazine when the slide travels in one direction, and means for moving the card holder independently of the slide to transfer the card to the former.

10. In a machine for making paper cups or cartons upon a former, a card magazine, a slide mounted to reciprocate beneath the magazine, a card holder movably mounted on the slide, means for retaining the card holder in normal position, means on said card holder adapted to withdraw a card from the magazine when the slide travels in one direction, and means for moving the card holder independently of the slide to transfer the card to the former.

11. In a machine for making paper cups or cartons, a card magazine, a slide reciprocating beneath the magazine, a card holder movable relative to the slide, means for moving the slide, and means controlled by the movement of the slide for moving the card holder relative to the slide.

12. In a machine for making paper cups or cartons, a card magazine, a slide reciprocating beneath the magazine, a card holder movable relative to the slide, means on the

holder for withdrawing the bottom card from the magazine, means for moving the slide, and means for moving the card holder relative to the slide.

5 13. In a machine for making paper cups or cartons, a card magazine, a slide reciprocating adjacent the magazine, a card holder movable relative to the slide, means on the holder for withdrawing the bottom 10 card from the magazine, cam mechanism for moving the slide, and independent cam mechanism for moving the holder relative to the slide.

14. In a machine for making paper cups 15 or cartons, a former, means for stripping the finished cup from the former, a card magazine, a slide moving adjacent thereto, a card

holder on the slide, and means for causing the holder to deliver a card to the former just after the stripping means has returned 20 to normal position.

15. In a machine for making paper cups or cartons, a former, means for stripping the finished cup from the former, a card magazine, a slide moving adjacent thereto, 25 a card holder on the slide, card receiving means on the former, and means for causing the holder to deliver a card to the receiving means just after the stripping means has returned to normal position. 30

In testimony whereof, I have hereunto subscribed my name.

HENRY F. SHAFFNER.
